TILLER

Seiya Noma, Toshikado Yamasaki, Kazuo Yoshida, Norio Orito, and Mineo Horiguchi, Tokyo, Japan, assignors to Iseki Agricultural Machinery Mfg. Co., Ltd., Matsu-yama, Japan

Filed Dec. 28, 1971, Ser. No. 213,239

Term of patent 14 years

Int. Cl. D15—03

U.S. Cl. D35—2 A

FIG. 1

FIG. 4

FIG. 6

FIG. 5

FIG. 3

FIG. 2

FIG. 7

FIG. 8

FIG. 1 is a front elevational view of a tiller showing our new design;

FIG. 2 is a right side elevational view of the tiller;

FIG. 3 is a side elevational view of the tiller opposite to the elevational view shown in FIG. 2;

FIG. 4 is a rear elevational view of the tiller;

FIG. 5 is a top plan view of the tiller;

FIG. 6 is a bottom plan view of the tiller;

FIG. 7 is a front perspective view as seen from the front of FIG. 4; and

FIG. 8 is a rear perspective thereof.

We claim:

The ornamental design for a tiller, as shown.
